Des. 202,546
Patented Oct. 19, 1965

202,546

STARTING PLATFORM FOR SWIMMING MEETS OR SIMILAR ARTICLE

John French, 240 Roxbury Road, Stamford, Conn.

Filed Dec. 28, 1964, Ser. No. 83,164

Term of patent 14 years

(Cl. D13—1)

Fig. 1.

FIGURE 1 is a perspective view of a starting platform for swimming meets or similar article showing my new design;

The dotted line showing on the drawing is for illustrative purposes only.

I claim:

The ornamental design for a starting platform for swimming meets or similar article, as shown and described.
